UNITED STATES PATENT OFFICE.

ELBERT J. JENKINS, OF MIDLAND, MICHIGAN, ASSIGNOR TO THE DOW CHEMICAL COMPANY, OF MIDLAND, MICHIGAN, A CORPORATION OF MICHIGAN.

PISTON RING.

Application filed September 23, 1920. Serial No. 412,302.

To all whom it may concern:

Be it known that I, ELBERT J. JENKINS, a citizen of the United States, and a resident of Midland, county of Midland, and State 5 of Michigan, have invented a new and useful Improvement in Piston Rings, of which the following is a specification, the principle of the invention being herein explained and the best mode in which I have contemplated 10 applying that principle, so as to distinguish it from other inventions.

I am aware that so-called light metal alloys have been heretofore utilized with more or less success for the construction of 15 pistons in internal combustion engines. Thus notably an alloy composed of aluminum as a predominant ingredient has been thus employed. I am not aware, however, that such alloy, still less an alloy of the 20 particular composition hereinafter set forth, has ever been utilized to form the rings which are an essential feature in the construction of internal combustion engines; in fact such an alloy composed principally of 25 aluminum would not be entirely satisfactory for this purpose as it is not a good bearing metal in contact with the cast iron of the cylinder wall, and pistons composed of such an alloy require to be given more than the 30 usual clearance for this reason and because of other features such as a tendency to "grow" which such alloys show.

The object of the present invention accordingly is to provide a piston ring of 35 light metal which will satisfactorily serve in the connection stated, by reason of its composition and construction. To the accomplishment of this and related ends such piston ring then is composed of the ingredients and includes the structural features hereinafter fully described and particularly set forth in the claims, the annexed drawing and the following description setting forth but one of the various ways in 45 which the principle of the invention may be used.

In said annexed drawing:—

Fig. 1 is a central sectional view more or less diagrammatic in character illustrating a typical internal combustion engine equipped with my improved piston rings; Fig. 2 is a similar section on a larger scale showing one such ring together with the adjacent walls of a cylinder and piston, 50 and Fig. 3 is a transverse section, i. e., in

the plane of such ring showing a portion of the ring with the adjacent walls of the cylinder and piston.

In its general features of construction, the internal combustion engine shown in 60 the drawing is of familiar design, comprising a cast iron cylinder 1, the upper portion of which is provided with a suitable water jacket 2 preferably integral therewith. Below the cylinder and enclosed in a suitable 65 case 3 is a crank 4, which is connected by means of a connecting rod 5 with a transverse pin 6 secured in the piston 7. The specific design of the latter forms no part 70 of the present invention except that as previously indicated, such piston is formed of a light metal alloy. Preferably the principal constituents of the alloy used in such piston, just as in the case of the piston rings 8 presently to be described, are magnesium and aluminum, magnesium being the predominating constituent. As most satisfactory for a piston thus designed for use 75 in an internal combustion engine I find an alloy composed of from 8 to 15 parts aluminum and the balance magnesium gives the most satisfactory results, such alloy having a specific gravity less than 2. The term "light metal," however, will be understood 80 to comprehend any alloy in which the predominant constituent is aluminum (sp. gr. 2.7) or magnesium (sp. gr. 1.72) or these 85 two metals taken together.

As just indicated, the composition of my improved piston rings 8 is the same as that 90 given as constituting the preferred composition of the piston itself. It will be understood, however, that my improved piston rings may be employed with other light metal pistons and for that matter with the 95 familiar cast iron piston that is ordinarily used in internal combustion engines, superior results being obtained in all cases.

Such rings are formed by casting a cylinder of the light metal alloy, such 100 cylinder having proper internal and external diameters, cutting off a section of such cylinder to form a ring of the desired height and then severing such ring at one point in its circumference. The severed 105 ring may then be rolled, peened, or otherwise manipulated to bring the ends thereof into proper relation and to give the ring the necessary degree of resiliency to insure close fitting contact between the same and 110

the cylinder wall when the ring is seated in the circumferential grooves therefor provided in the piston. The manner in which the rings are thus seated in the grooves in question is clearly shown in the detail views of Figs. 2 and 3.

I have found that a piston ring composed of a light metal alloy and specifically one containing from 8 to 15 per cent of aluminum and the balance magnesium, has a much greater heat conductivity than the rings ordinarily used, so that the heat from the piston, forming as the latter does the go-between between the piston and the cylinder wall is quickly carried to the latter. At the same time the alloy having the composition stated is not abrasive to cast iron and so insures that the cylinder wall will not be scored from the action of such rings on any type of piston. The weight being small in comparison even with light metal pistons in which aluminum instead of magnesium is the predominating ingredient, helps correspondingly to decrease the weight of the reciprocating parts, while the natural tension or resiliency of this special alloy is sufficient at all times to keep the rings in close fitting contact with the cylinder wall and so insures good compression in the engine.

Other forms may be employed embodying the features of my invention instead of the one here explained, change being made in the form of construction, provided the

elements stated by any of the following 35 claims or the equivalent of such stated elements be employed.

I therefore particularly point out and distinctly claim as my invention:—

1. As a new article of manufacture, a 40 piston ring for an internal combustion engine composed of a light metal alloy, in which the predominant constituent is magnesium.

2. As a new article of manufacture, a piston ring for an internal combustion engine composed of a light metal alloy, in which the predominant constituent is magnesium and the principal remaining constituent is aluminum. 45

3. In an internal combustion engine, the combination with a cast iron cylinder, of a piston therefor composed of a light metal alloy, and piston rings carried by said piston and likewise composed of a light 55 metal alloy, the predominant constituent of which is magnesium.

4. In an internal combustion engine, the combination with a cast iron cylinder, of a piston therefor composed of a light metal 60 alloy, and piston rings carried by said piston and likewise composed of a light metal alloy, the predominant constituent of which is magnesium, and the principal remaining constituent is aluminum. 65

Signed by me this 20th day of September, 1920.

ELBERT J. JENKINS.
